METAL COATING APPARATUS

Frederick C. Brightly, Jr., Oak Park, Ill.

Application March 27, 1946, Serial No. 657,537

5 Claims. (Cl. 212—131)

1

The present invention relates generally to improvements in metal coating apparatus, and has particular reference to a new and improved apparatus for coating metals by the hot dip process, as, for example, for galvanizing, tinning and lead coating.

One of the primary objects of the present invention is to provide a novel metal coating apparatus which greatly reduces the arduous manual labor that is normally required, and which affords a uniform and flexible control of the operation.

Another object is to provide a new and improved metal coating apparatus in which the material to be galvanized is translated from station to station, and elevated and lowered by power means, thereby permitting the use of large baskets for handling the material, and utilization of the full capacity of the kettle containing the molten metal coating bath.

A further object is to provide a novel metal coating apparatus in which the timing of various movements of the material at successive stages in the operation is subject to accurate adjustment in accordance with the specific requirements of the work pieces, as determined, for example, by size, shape, thickness, and composition.

Another object is to provide a new and improved metal coating apparatus which carries out automatically those steps of the operation that are most hazardous when performed manually, which greatly reduces the number of operators or attendants that are required, and which eliminates the human factor as a cause of possible error in passing the material through the hot coating bath.

A further and more specific object is to provide a novel metal coating apparatus which comprises a trolley running on a closed overhead rail circuit and driven by a variable-speed electric motor, and a hoist on the trolley for carrying the work basket and operable by a reversible variable-speed electric motor to elevate and lower the basket.

Another object is to provide a new and improved metal coating apparatus of the foregoing character in which the direction of rotation of the hoist motor is controlled by reversing the polarity, and the speed of both the trolley motor and hoist motor is controlled by varying the voltage of the impressed electric current, these controls being effected both manually and automatically through the medium of individually charged segments of a series of trolley wires following along the supporting rail circuit.

2

Further objects and advantages will become apparent as the description proceeds.

In the accompanying drawings,

Fig. 1 is a plan view of a galvanizing apparatus embodying the features of my invention.

Fig. 2 is an elevational view, partially in vertical section, of the operating run of the apparatus.

Fig. 3 is a transverse vertical section, on an enlarged scale, taken along line 3—3 of Fig. 1, and illustrating the basket handling mechanism.

Fig. 4 is a fragmentary detail view, partially in longitudinal section and on a still larger scale, of one of a plurality of parallel segmental trolley wires or conductors forming part of the electrical control circuits of the apparatus.

Fig. 5 is a fragmentary perspective view, with the elements shown in exploded relation, of one of the insulating connections for joining the contiguous ends of the various segments of the trolley wires.

Fig. 6 is a transverse vertical sectional view taken along line 6—6 of Fig. 4.

Fig. 7 is an enlarged side elevational view of the trolley and hoist assembly.

Fig. 8 is a diagrammatic representation of the electrical operating and control circuits of the apparatus.

While the invention is susceptible of various modifications and alternative constructions, I have shown in the drawings and will herein describe in detail several embodiments, but it is to be understood that I do not thereby intend to limit the invention to the specific forms disclosed, but intend to cover all modifications and alternative constructions falling within the spirit and scope of the invention as expressed in the appended claims.

Referring more particularly to the drawings, the metal coating or galvanizing apparatus, constituting the exemplary embodiment of the present invention, comprises various operating units for treating the material sequentially in the successive steps of a hot dip galvanizing process. These operating units are arranged in series alignment, and may be conventional in type and construction. In the present instance, the units comprise a dryer 10, a galvanizing kettle 11, a centrifuge 12, a quenching tank 13, and, if desired, an inspection table or conveyor 14. The details of the operating units 10 to 14, per se, form no part of the present invention, and hence are described only in general respects to facilitate understanding of their functions in the apparatus. Preferably, all of the units are mounted at suitable levels on a solid foundation 15.

The dryer 10, in the form shown, comprises a horizontal mesh conveyor 16, preferably of Monel metal, driven by an electric motor 17, a heating element 18 over the conveyor and preferably consisting of a steam heat radiator, and a series of overhead fans 19 for directing blasts of hot air from the heating element downwardly through the conveyor tunnel. The material to be galvanized, which may consist at different times of duplicate work pieces of widely varying shapes, and sizes, is customarily cleaned in an acid pickling bath and pre-dipped in a flux solution, and is then placed on the inlet end of the conveyor 16 to be dried. The hot air blasts in the dryer 10 serve to remove surface moisture from the work pieces preparatory to the galvanizing operation.

The galvanizing kettle 11 may be of any suitable type, and in the present instance comprises a long rectangular tank 20 supported on a depressed portion of the foundation 15 at a lower level than the dryer 10, and having compartments 21 and 22 respectively in opposite end portions defined by a stopper or dam 23 and in intercommunication beneath the latter. The first compartment 21 normally contains a galvanizing bath 24 of zinc covered with a layer or blanket of a suitable fluxing agent, such, for example, as sal ammoniac or zinc ammonium chloride. The second compartment 22 normally contains a clear zinc bath 25, the stopper 23 projecting downwardly into the zinc sufficiently to confine the layer of flux to the surface of the bath 24. Any suitable heating means, represented at 26, may be provided in the lower portion of the kettle 11 to maintain the zinc in a molten state. After the removal of moisture in the dryer 10, the material or work pieces to be galvanized are taken from the discharge end of the conveyor 16, and loaded into a suitable basket 27 to facilitate handling in the subsequent steps of the operation. The baskets for this purpose are usually cylindrical in shape, open at the top, provided with a bail 28, and formed with apertures in the peripheral and bottom walls to permit free passage therethrough of the fluid zinc for surface contact with the work pieces. It will be understood that after leaving the dryer 10, the loaded basket 27 is transferred to the galvanizing kettle 11, and immersed for predetermined periods of time first in the bath 24 and then in the bath 25 in successive dipping operations. It has been customary heretofore to transport the basket and to lift it into and out of various operating units by manual labor, thus entailing arduous work under adverse conditions necessitating frequent shutdowns and limiting the size of basket that can be used.

The rate of speed at which the basket 27 is dipped or immersed in the first zinc bath 24 should be so controlled that any residual moisture still on or in the work pieces will not be carried downwardly below the surface layer of flux into the metallic zinc, but will be driven off by the heat of the flux. If entrained moisture were to be carried into the metallic zinc, it would be converted suddenly and violently into superheated steam which might cause actual eruption of zinc and flux from the kettle 11, and thus result in loss of these materials and in injury to any operator or bystander. Such condition is always a possibility due to human errors if immersion is effected manually.

To obtain both efficient and proper coating of the work pieces with zinc, it is important that

after full immersion of the loaded basket 27 in the first bath 24, the basket moved along the bath at such a rate of speed that the work pieces will have been heated to the temperature of the zinc by the time the basket reaches the discharge end of the compartment 21. Such equalization of temperature is necessary to effect proper galvanizing. The time required must be varied in accordance with the character and condition of the work pieces, and depends for example on the size, shape, thickness, and composition of the material. Here again, if translation of the basket along the bath is effected manually, the element of human error in judging the time of immersion may result in nonuniform and unsatisfactory galvanizing.

The centrifuge 12 may be of any suitable construction, and in the present instance is shown as comprising a spinner 29 enclosed within a housing 30 and adapted to receive the loaded basket 27 after removal from the bath 25. The spinner 29 is rigidly supported on the upper end of a vertical drive shaft 31 connected through a clutch-controlled power transmission 32 to an electric drive motor 33. When the basket 27 is placed in the centrifuge 12, it is whirled or rotated at a high rate of speed, and the resulting centrifugal force serves to throw off any excess zinc and zinc drippings from the basket and contents.

After having been centrifuged, the basket 27 containing the now galvanized work pieces is lowered into a dumping frame 13a in the quench-tank 13, and the work pieces dumped into a hopper 13b from which they fall into a quenching bath, such as water. The hopper 13b is automatically operable by a discharge mechanism 34 for transferring the finished work pieces onto the inspection table or conveyor 14, or to any other suitable conveyance.

The present invention resides primarily in the provision of novel power operated means for conveying the loaded basket 27 from the dryer 10 along the line of operation, and, at predetermined points in the path of travel, lifting and lowering the basket so as to transfer it successively to the zinc baths 24 and 25, the centrifuge 12 and the quenching tank 13, and when emptied back to the initial loading station. The controls for the power means are subject to graduation and selective adjustment so as to provide in each individual instance the desired rate of speed for elevating, lowering, and translating the basket. In the present instance, the controls are arranged for manual actuation at the loading, centrifuging and quenching stations, and for automatic actuation during the galvanizing steps and during the rapid return of the empty basket to the initial starting position. Consequently, the immersion of the work pieces in the zinc baths is accurately timed to insure efficient and reliable galvanizing over a wide range of operating requirements.

In the preferred embodiment of the invention, the conveying apparatus comprises a wheeled carriage or trolley 35 running on an overhead rail or track 36, and adapted to be driven by a variable-speed electric motor 37 carried therewith. Supported on the trolley 35 for movement therewith is a hoist 38 having a drum 39 operable by a reversible variable-speed electric motor 40, and serving through a suspension cable 41 to elevate and lower a suitable hook 42 adapted to engage the bail 28 of the basket 27.

The monorail 36 may be of any suitable form,

and extended to define any desired path of travel providing a run along the various operating units of the galvanizing apparatus. Preferably, the monorail 36 is in the form of a continuous elongated loop or circuit having an operating run along one side from the loading station 43 at the discharge end of the dryer 10 successively past units 11, 12, 13 and 14, and a return run from the unit 14 along the other side back to the starting point. In sectional form, the rail 36 may be of I-beam structure having upper and lower side flanges 44 and 45. A plurality of hanger members 46, located at regularly spaced points about the rail circuit, are rigidly connected at their lower ends to the upper flanges 44 of the rail 36, and adapted to be connected at their upper ends to a suitable overhead support, such as roof trusses or the like (not shown).

A plurality of bus bars or conductors are supported from and extend along opposite sides of the rail 36 for supplying current to the motors 37 and 40. In the present instance, six of such bus bars 47, 48, 49, 50, 51 and 52 are provided, the two bars 47 and 48 being disposed along the outside of the rail 36, and adapted to supply current under selective voltage control for the trolley motor 37, and the remaining four bars 49, 50, 51 and 52 extending along the inner side of the rail and being adapted to supply current reversibly and also under selective voltage control for the hoist motor 40. The bus bars 47 to 52 preferably are cylindrical in form to constitute trolley wires supported for rolling contact with grooved trolley wheels 53 to 58 on the carriage 35. To provide suitable supporting means for the bus bars 47 to 52, a plurality of transverse angle bars 59 extend across the top of the rail 36 at appropriately spaced points along the rail circuit, and are rigidly secured intermediate their ends to the upper rail flanges 44. Preferably, the outer ends of the bars 59 are additionally connected by inclined brace members 60 to the rail 36. The bus bars 47 to 52 are individually connected in suspended relation to the underside of each of the transverse bars 59 by means of stand-off insulators 61.

The trolley or carriage 35, in its preferred construction, comprises a suitable frame or case 62 having spaced bearing housings 63 at opposite sides of the rail 36. Two pairs of flanged wheels 64 are fixed on shafts 65 journaled in the bearing housing 63, and are in rolling engagement with the upper surfaces of the lower flanges 45 of the rail 36 to support the trolley 35 in suspended position. The drive motor 37 is connected through a suitable power transmission to the two wheels 64 at one side of the rail to roll the trolley 35 along the rail at selective predetermined rates of speed. More particularly, the motor 37 has an armature shaft 66 connected through a belt 67 and pulleys 67a and 67b to a worm shaft 68a. A worm 68 on the shaft 68a meshes with a worm wheel 69 on a shaft 69a connected through a link chain and sprockets 69b to a shaft 70 in turn connected through two sets of bevel gears 71 and gears 71a in one of the bearing housings 63 respectively to the related wheel shafts 65. The motor 37 and all mechanical elements of the power transmission are enclosed within the case 62.

The grooved wheels 53 to 58 constitute electrical contact elements for taking off current from the conductors 47 to 52 for the carriage and hoist motors 37 and 40. In the present instance, the wheels 53 to 58 are rotatably jour-

nailed, with good electrical contact, in bearings 73 respectively on the free upper ends of a like number of spring arms 74 to 79 rigidly anchored at their lower ends on the trolley case 62. The arms 74 to 79 are insulated from the case 62 by interposed dielectric blocks 80 and 81, and are normally flexed or curved to maintain the wheels 53 to 58 under pressure in rolling contact with the conductors 47 to 52 as the trolley 35 moves along the track 36. The lower end of each arm is provided with a lug 81a for attachment of a motor lead wire.

The arms 74 and 75 are connected through electric lead wires or lines 82 and 83 in parallel across the armature 84 and field 85 of the motor 37. In the case of the hoist motor 40, the arms 76 and 77 are connected through lines 86 and 87 to opposite ends of the field 88, and the arms 78 and 79 are connected to lines 89 and 90 adapted to be connected reversibly through a limit switch 91 to opposite sides of the armature 92.

To control the speed of operation of the motors 37 and 40 along or at different sections of the rail circuit, the various bus bars 47 to 52, although in the form of continuous trolley wires, are each divided into a series of insulated electrical segments, and certain related segments are connected in pairs through individual circuits to a suitable source of electrical energy so as to permit of independent voltage control. The contiguous ends of the series of conductor segments in each trolley wire may be mechanically connected in any suitable manner affording electrical insulation. The segments are made of a conducting material, such as copper tubing. As shown in Figs. 4 to 6, the ends of the segments are separated by a cylindrical spacer 93 made of a suitable insulating material, and having the same outside diameter as the segments so as to present a smooth and uninterrupted connection over which the associated contact wheel can roll from one segment to the other. The spacer 93 is formed at opposite ends with reduced cylindrical pilot extensions 93a extending snugly into the open bores in the contiguous ends of the conductor segments to maintain the elements in axial alignment. The upper side of the spacer 93 is formed with a longitudinal rib 94 coextensive in length therewith. Opposite ends of the rib 94 are fitted into slots 95 formed in the upper sides of the conductor segments. To secure the various elements in rigid assembly, suitable metal clamp plates 96 are bolted against opposite sides of the end portions of the rib 94, and are formed with arcuate flanges 97 welded to the segments along opposite sides of the slots 95. The plates 96 afford a convenient means for the attachment of electrical lead wires to the segments.

The number and lengths of the conductor segments are determined by the specific operations to be performed in the galvanizing process. Considering first the travel of the trolley carriage 35, trolley wires 47 and 48 are interrupted at five points *a* to *e* along the operating side of the loop or circuit to provide insulated segments *a*—*b*, *b*—*c*, *c*—*d*, *d*—*e*, and *e*—*a*. The first pair of segments *a*—*b* are located at the loading station 43 adjacent the discharge end of the dryer 10, the point *a* being the starting point of each operating cycle. These segments are normally disconnected from the source of electric current, but are adapted to be connected through manual control whenever the trolley 35, with a loaded basket of work pieces suspended on the hook 42, is to be started through the cycle. Electric current is

adapted to be supplied to the segments *a*—*b* from main lines 98 and 99 through master switch elements 100 and a normally open control switch 101 adapted to be closed by means of a hand actuator 102, the circuit being from main line 98 through switch element 100, line 103, adjustable rheostat 104, and line 105, to one segment *a*—*b*, and from main line 99 through switch element 100, line 106, control switch 101 and line 107 to the other segment *a*—*b*.

The second pair of segments *b*—*c* extend between the dryer 10 and the galvanizing kettle 11, and are constantly energized, the connecting circuits being from main line 98, through master switch element 100 and line 108 to one of the segments, and from main line 99 through master switch element 100, line 109, adjustable rheostat 110, and line 111 to the other of the segments. The rheostats 104 and 110 are adjustable to vary the speed of the motor 37, and preferably are set to move the trolley 35 at a comparatively fast rate of speed. In starting the operation, the switch 101 is closed and is held closed until the trolley wheels 53 and 54 pass from the segments *a*—*b* to the segments *b*—*c*, the latter automatically taking over control to effect continued movement of the trolley 35.

The third pair of segments *c*—*d* extend over the galvanizing kettle 11, and also are constantly energized, the connecting circuits being from main line 98 through master switch element 100, and line 112 to one of the segments, and from main line 99 through master switch element 100, line 113, adjustable rheostat 114 and line 115 to the other of the segments. As the trolley wheels 53 and 54 pass from the segments *b*—*c* to the segments *c*—*d*, travel of the trolley 35 is continued automatically but at a rate of speed determined by the setting of the rheostat 114. Along this section of the rail circuit, the work basket is immersed in the galvanizing kettle and moved slowly therethrough at a rate providing sufficient time for the work pieces to attain the temperature of the zinc bath. Consequently, the rheostat 114 is adjusted to provide a commensurately low voltage, and the adjustment may be varied in accordance with the requirements of the work pieces, which are determined by such factors as size, thickness and composition.

The fourth pair of segments *d*—*e* extend from the galvanizing kettle 11 along the centrifuge 12 and quenching tank 13, and are normally de-energized but adapted for energization through manual control. The connecting circuits are from main line 98 through master switch element 100, line 116, rheostat 117 and line 118 to one of the segments, and from main line 99 through master switch element 100, line 117a, normally open control switch 118a, and line 119 to the other segment. The control switch 118a is adapted to be closed by means of a hand operator 120. Upon movement of the trolley wheels 53 and 54 from the segments *c*—*d* to the segments *d*—*e*, the trolley 35 will come to rest unless the control switch 118a is closed. Consequently, the trolley 35 can be moved into position at any point along the segments *d*—*e*, as, for example, into position over the centrifuge 12 and subsequently over the quenching bath 13, by manually closing the control switch 118a and keeping it closed until the desired movement has been effected.

The fifth pair of segments *e*—*a* extend from the quenching tank 13 around the remaining portion of the rail circuit back to the starting point *a*, and are constantly energized, the con-

necting circuits being from main line 98, through master switch element 100, and line 121 to one of the segments, and from main line 99, through master switch element 100, line 122, adjustable rheostat 123 and line 124 to the other segment. These segments serve to provide the electric power for returning the basket 27, after having been emptied into the quenching tank 13, back to the loading station 43 for another load of work pieces. To start the return movement, the switch 118a is closed and held closed until the trolley wheels 53 and 54 pass from the segments *d*—*e* to the segments *e*—*a*, whereupon the latter automatically take over control to effect continued movement of the trolley 35 until the wheels run onto the de-energized segments *a*—*b*. The rheostat 123 in this instance is adjusted to effect a rapid return movement of the trolley 35.

The circuits to the motor 37 are momentarily interrupted each time the trolley wheels 53 and 54 cross one of the insulated points *a* to *e*, but the momentum of the trolley 35 is sufficient to carry the wheels across into electrical contact with the immediately succeeding conductor segments.

Considering now the operation of the hoist 38, the trolley wires 49 to 52 are interrupted at nine points, *f* to *n*, along the operating side of the loop or circuit to provide insulated segments *f*—*g*, *g*—*h*, *h*—*i*, *i*—*j*, *j*—*k*, *k*—*l*, *l*—*m*, *m*—*n*, and *n*—*f*, which are correlated in location to the segments *a*—*b* to *e*—*a*, so as to control the operation of the hoist in timed relation to the travel of the trolley.

The first set of segments *f*—*g* in the hoist control circuits coincide in length and position with the segments *a*—*b*, and are normally de-energized, but adapted to be connected to the main lines 98 and 99 through manual control circuits for selectively effecting forward and reverse operation of the hoist motor 40. More particularly, the "up" circuit is from main line 98, switch element 100, line 103, interlock switch 125, and line 126 to the pair of segments *f*—*g* in the trolley wires 50 and 52, and from main line 99 through switch element 100, line 106, normally open manual control switch 127, and line 128, to the pair of segments *f*—*g* in the trolley wires 49 and 51. The "down" circuit is from main line 98 through switch element 100 and line 103 to the pair of segments *f*—*g* in the trolley wires 50 and 51, and from main line 99 through switch element 100, line 106, normally open manual control switch 129, and line 130 to the pair of segments *f*—*g* in the trolley wires 49 and 52. A magnetic coil 131 is connected across the lines 103 and 130, and serves when energized to open the interlock switch 125. The control switches 127 and 129 are adapted to be closed by means of suitable hand actuators 132 and 133. It will be noted that the "up" and "down" circuits are the same except that the polarity of the segments *f*—*g* in the trolley wires 51 and 52 connected to the armature 92 of the motor 40 is reversed. When the trolley 35 is at the loading station 43, switch 129 is closed to effect operation of the hoist motor 40 in a direction to lower the basket 27 into convenient position for loading. After the basket has been loaded, the switch 127 is closed to reverse the operation of the motor 40 so as to raise the loaded basket into elevated position.

The switch 101 is now closed to advance the trolley 35 to the galvanizing kettle 11, the basket

27 being carried in a straight horizontal path indicated by the dotted line $o-p$ (see Fig. 2). Since it is unnecessary to operate the hoist 38 during this approach movement, the next set of segments $g-h$ are not connected to the source of electric current, but are dead and disable the circuits for the hoist motor 40.

Upon movement of the trolley 35 from the segments $b-c$ to the segments $c-d$, the trolley wheels 55 to 58 for the hoist 38 pass from the dead segments $g-h$ to the live segments $h-i$ which are constantly energized, the connecting circuit being from main line 98, through switch element 100, and line 134 to the segments in the trolley wheels 50 and 51, and from main line 99, through switch element 100, line 135, adjustable rheostat 136, and line 137 to the segments in trolley wires 49 and 52. As a result, the motor 40 will operate to automatically lower the loaded basket into the inlet end of the galvanizing kettle 11 at the rate determined by the adjustment of the rheostat 136. The resultant movement of the basket 27 thus follows the inclined $p-q$.

While any suitable means may be provided for stopping the motor 40 when the loaded basket 27 has been lowered to the desired level in the zinc bath 24 beneath the blanket of flux, the length of the segments $h-i$ is so determined in relation to the speed of travel of the trolley 35 and the speed at which the basket is lowered, that the trolley wheels 55 to 58 will pass from the live segments $h-i$ to the segments $i-j$ to interrupt the motor circuits and thereby stop the basket at the desired level. The segments $i-j$ are not energized, and extend along the length of the bath 24. Consequently, in the continued movement of the trolley 35, the basket 27 will be moved at this fixed low level slowly through the bath 24 along the path $q-r$.

When the basket 27 reaches the discharge end of the bath 24, the trolley wheels 55 to 58 will pass from the dead segments $i-j$ successively along the live segments $j-k$ and $k-l$ to the dead segments $l-m$, thereby automatically transferring the basket along the path $r-s-t$ from the bath 24 over the dam or stopper 23 to the bath 25. The circuit for energizing the segments $j-k$ has a polarity operating the motor 40 in the "up" direction, and is from main line 98, through switch element 100, line 138, rheostat 139 and line 140 to the segments in the trolley wires 50 and 52, and from line 99, through switch element 100, and line 141 to the segments in trolley wires 49 and 51. The circuit for the segments $k-l$ reverses the polarity of the motor 40, and is from main line 99, through switch element 100, line 142, adjustable rheostat 143, and line 144 to the segments in the trolley wires 50 and 51, and from main line 99, through switch element 100 and line 145 to the segments in the trolley wires 49 and 52. The two sets of segments $j-k$ and $k-l$ are comparatively short, and the rheostats 139 and 143 are adjusted to effect operation of the motor 40 at a comparatively high rate of speed so as to obtain a quick transfer of the loaded basket 27 from the bath 24 to the bath 25.

As the trolley wheels 55 to 58 pass from the segments $k-l$ to the dead segments $l-m$, the circuit for the motor 40 is interrupted to maintain the basket 27 at the desired level of immersion in the bath 25 as it is moved by the trolley 35 along the path $t-u$ to the discharge end of the galvanizing kettle 11.

At the discharge end of the galvanizing kettle, the trolley wheels 55 to 58 for the hoist motor 40

pass from the dead segments $l-m$ to the normally deenergized segments $m-n$, and the trolley wheels 53 and 54 for the trolley motor 37 pass from the segments $c-d$ to the segments $d-e$, thus stopping the trolley 35 unless and until the manual switch 118a is closed, as previously described. At this point in the operation, the basket 27 is adapted to be lifted from the bath 25 by energizing the segments $m-n$ through manual control, the circuit being from main line 98, through switch element 100, line 146, interlock switch 146, and line 147 to the segments in trolley wires 50 and 52, and from main line 99, through contact element 100, line 148, normally open manual switch 149 and line 150 to the segments in the trolley wires 49 and 51. When the switch 149 is closed, as by the hand operator 151, the armature polarity is such that the motor 40 will operate in an "up" direction to elevate the basket along the path $u-v$.

In the subsequent travel of the trolley 35 along the segments $d-e$, the hoist motor 40 can be operated at will in either forward or reverse direction to lower or elevate the basket 27 as required in the subsequent steps of the coating operation. The "down" circuit for the segments $m-n$ is from line 98, through switch element 100, and line 146 to the segments in the trolley wires 50 and 51, and from main line 99, through switch element 100, line 148, normally open switch 152 provided with a hand actuator 153, and line 154 to the segments in the trolley wires 49 and 52. A magnetic coil 155 is connected across the lines 146 and 154, and is adapted, when energized, to open the interlock switch 146. It will be understood that all of the switch elements 100 are incorporated in one master switch for controlling the entire electrical system.

After the loaded basket 27 has been lifted from the galvanizing kettle 11 or while lifting same, the switch 118a is closed to move the basket along the path $v-w$ into centered position over the centrifuge 12. Then, the switch 152 is closed for a sufficient time to lower the basket into the spinner 29. After the centrifuging operation, the switch 149 is closed to lift the basket 27 from the centrifuge 12. The switch 118a now is again closed to move the basket 27 along the path $w-x$ into centered position over the quenching tank 13. Then, the switch 152 is closed to lower the basket 27 into the dumping frame 13a which is operated to dump the work pieces into the chute 13b. The switch 149 is then closed to lift the empty basket from the quenching tank 13. Finally, the switch 118a is closed to cause the trolley 35 to move from the segments $c-e$ to the segments $e-a$ which automatically take over control to effect rapid return of the trolley with the empty basket to the starting segments $a-b$. The segments $n-f$ are not energized since the basket 27 is carried in elevated position on the return movement.

It will be evident that I have provided a new and advantageous metal coating apparatus for translating a loaded work basket and for elevating and lowering the basket at predetermined points in the translation by power means so as to eliminate the arduous manual labor which has heretofore been required and to reduce the number of attendants required to carry out the coating operation.

Preferably the operation is subject to manual control at the points where the time required is indeterminate, for example, at the loading, centrifuging, and quenching stations, but is fully

automatic in passing the loaded basket through the galvanizing kettle 11, the basket being automatically lowered and elevated to immerse the work pieces first in the bath 24 and then in the bath 25, and being traversed in each instance through the bath, and the rates of movement being subject to adjustment in accordance with the operating requirements. As a result, the hazard normally involved in the dipping operations is eliminated, and these operations are carried out efficiently and with uniformity in repeated cycles. Since the basket need not be handled manually at any time, it can be larger than has been considered practicable heretofore, so as to utilize the full galvanizing capacity of the kettle.

I claim as my invention:

1. A conveying apparatus comprising, in combination, a rail adapted to be suspended from an overhead support, a trolley supported by said rail for movement therewith, a variable speed electric motor for effecting movement of said trolley along said rail, a hoist carried by said trolley for movement therewith to support a work piece, a reversible electric motor for elevating and lowering said work piece, a first pair of trolley wires for supplying electric current to said trolley motor, a second pair of trolley wires for supplying electric current to the field of said hoist motor, a third pair of trolley wires for supplying electric current to the armature of said hoist motor, each of said three pairs of trolley wires secured to said rail and extending therewith, each pair of wires comprising a series of axially aligned electrical conducting segments insulated from each other, and forming corresponding pairs of conducting segments, a plurality of individual rolling contacts carried by said trolley and contacting said wires, separate electric operating circuits connecting the contacts contacting said first, second and third pairs of wires respectively to the trolley motor, and to the field and to the armature of said hoist motor, a plurality of individual electric energizing circuits for connecting said first pairs of conducting segments for said trolley motor to a source of electric current, and a plurality of additional electrical energizing circuits for connecting certain of said second and third pairs of conducting segments for said hoist motor with alternately reversed poles of a source of direct current to alternately reverse the direction of current supplied to said hoist motor to reverse the direction of rotation thereof, each energizing circuit for said pairs of conducting segments for said trolley motor including an adjustable rheostat for controlling the motor speed.

2. A conveying apparatus comprising a rail adapted to extend along and to be mounted over a plurality of operating units arranged in functional position, a trolley supported on and movable along said rail, a variable speed motor carried by said trolley for driving the trolley along said rail, an electrical circuit for energization of the motor to drive said trolley progressively along said rail at a succession of pre-selected rates of speed, said circuit including separate closely spaced aligned pairs of conductors extending along the length of said rail, means connecting each of said pairs of conductors to a source of electric energy, and a rheostat for controlling the amount of energy introduced into each of said conductors and thereby the speed of travel of said trolley, a hoist carried by said trolley, a reversible variable speed electric hoist motor

also carried by said trolley, work elevating and lowering means on said hoist for carrying a work piece, and means for energizing the armature and field of said hoist motor to selectively operate 5 said work elevating and lowering means in predetermined time relation to the movement of said trolley, said means including a pair of conductors extending along the length of said rail, an operating circuit connecting said conductors 10 to the field of said hoist motor, means connecting said conductors to a source of direct current, a second pair of conductors extending along the length of said rail and divided into a plurality of closely spaced separate insulated segments, an 15 operating electric circuit for connecting said second pair of conductors to the armature of said hoist motor, and means individually connecting each of the segments of said second pair of conductors to a source of direct current with adjacent segments being alternately connected to the positive and negative sides of said source of current to reverse the polarity of the armature of said hoist motor to thereby alternately elevate and lower said work piece as said trolley is advanced along said rail.

3. A conveyor apparatus comprising a monorail extending through a closed loop and suspended from an overhead support over a series of units arranged in functional alignment, said 20 monorail having side flanges extending outwardly therefrom, a trolley having a case, traction wheels journaled in said case and running on side flanges of said rail, a variable speed electric motor mounted in said case for driving said trolley 25 along said rail, a hoist mounted on said trolley for movement therewith and having means for supporting a work piece, a reversible variable speed electric motor for elevating and lowering said work piece supporting means, a plurality 30 of pairs of trolley wires extending in closed loops around said rail and each pair comprising a series of closely spaced aligned parallel electrical conducting pairs of corresponding segments insulated from each other, means for supporting said trolley wires from said rail, an individual electrical contact for each wire supported by said rail, electric operating circuits connecting the contacts for one pair of wires to the trolley motor, electric operating circuits connecting the contacts for the other pairs of wires to the armature and field of said hoist motor, and a plurality 35 of individual electric energizing circuits for connecting certain of said conducting segments respectively to a source of electric current, each energizing circuit including an adjustable impedance for controlling the impressed voltage, certain of said energizing circuits being closed to constantly energize the associated segments, the remainder of said energizing circuits being normally open and adapted to be closed at will, the energizing circuits for successive pairs of segments connected to said armature being alternately reversed in polarity to alternately raise and lower said work supporting means as the 40 trolley is advanced along the rail.

4. A conveyor adapted for advancing work through a coating apparatus, comprising a track, a trolley carried by said track for movement therewith, means for advancing said trolley along said track, a hoist carried by said trolley and having work elevating and lowering means, a reversible, variable speed motor for driving said hoist to elevate or lower said work elevating and lowering means, a first pair of conductors 45 insulatedly carried by said track and extending

along the length thereof for electrically energizing the field of said hoist motor, a second pair of conductors for energizing the armature of said hoist motor, each of said conductors being divided into aligned closely spaced segments separated by insulating gaps, and forming corresponding pairs of conducting segments, and individual control circuits for said pairs of segments, said circuits including additional conductors connecting the segments of said pairs of conductors to a source of direct current to energize the field and armature of said hoist motor, the additional conductors connecting said second pair of conductors to said source being each alternately connected to the positive and negative poles of said source of current to successively reverse the polarity of the armature and the direction of rotation of the hoist motor, thereby alternately elevating and lowering the work supporting means as the trolley is advanced along said track.

5. A conveyor adapted to control movement of work in horizontal and vertical planes which comprises an overhead looped horizontal track, a trolley suspended on said track, a hoist on said trolley, work supporting means carried by said hoist, a variable speed electric motor carried by said trolley for advancing the trolley along the track, a reversible electric motor for driving the hoist to raise and lower said work supporting means, two sets of conductors extending along said track, each of said conductors being composed of a plurality of aligned closely spaced segments, separate circuits for energizing the segments of said conductors, and contactors on the trolley connecting one set of conductors with the motor for driving the trolley and the other set of conductors with the motor for driving the

10 hoist, said circuits including means for connecting the individual segments of said one set of conductors to a source of electrical energy, an adjustable impedance for controlling the impressed voltage in said one set of conductors and thereby the speed of travel of said trolley, means for alternately connecting the individual segments of said other set of conductors to the positive and negative poles of a source of direct current to alternately reverse the polarity of current introduced into the reversible hoist motor, thereby elevating and lowering the work supporting means of the hoist while said trolley is advanced along said track.
